APPARATUS FOR SCARFING BILLETS AND
THE LIKEReidar J. Nicolaisen, New York, N. Y., assignor
to Air Reduction Company, Incorporated, a
corporation of New York

Application July 10, 1947, Serial No. 760,157

8 Claims. (Cl. 266—23)

1

This invention relates to apparatus for scarfing or desurfacing ferrous metal bodies, and more particularly to apparatus for simultaneously scarfing all four faces of billets, blooms, slabs, and other work-pieces of rectangular cross-section.

Scarfing machines have already been proposed for simultaneously scarfing all four faces of a billet or the like in which four scarfing heads are adjustably mounted so that a succession of work-pieces of the same or different cross-sectional dimensions can be scarfed. However, in some of the machines previously proposed it is necessary to position one pair of adjacent scarfing heads in a different plane from the other pair so that the heads will not strike or interfere with one another when they are moved inwardly from their positions for scarfing a work-piece of maximum size to their positions for scarfing a smaller work-piece. In other machines rather complicated mechanism is required to provide for the various movements the scarfing heads must have when they move into operative relation with the work-piece and when they accommodate themselves to work-pieces of different cross-sectional dimensions, and even so, the danger of the scarfing heads striking or interfering with one another when they are so moved is not completely avoided.

Another disadvantage of the previously proposed scarfing machines is that certain movements of the scarfing heads are provided for by guideways, and by slides mounted to move rectilinearly in them. The proper functioning of such parts is more likely to be interfered with by the accumulation of dirt and slag from the scarfing operations than pivoted connections.

One object of this invention is to provide improved scarfing apparatus adapted to simultaneously scarf all four faces of metal bodies of rectangular cross-section and of various cross-sectional dimensions, and having scarfing heads or scarfing tips so mounted that they can always be moved without interference between them into an operative position with respect to the work-piece even though they may at times lie in the same general transverse plane.

Another object is to provide scarfing apparatus adapted to simultaneously scarf all four faces of a work-piece of rectangular cross-section in which all movements of the scarfing tips which cause them to accommodate themselves to work-pieces of various cross-sectional dimensions are provided for by pivotal connections as distinguished from connections of the sliding type.

A further object of the invention is to provide scarfing apparatus adapted to simultaneously scarf all four faces of work-pieces of rectangular cross-section and of various cross-sectional dimensions which is simpler in construction than

2

apparatus previously proposed for the same purpose.

Scarfing apparatus embodying the invention is illustrated in the accompanying drawings, in

5 which:

Figure 1 is a plan view of the apparatus;

Fig. 2 is a side elevation of the apparatus shown in Fig. 1;

Fig. 3 is an end elevation of the apparatus 10 shown in Fig. 1 drawn to a larger scale and viewing the apparatus from the left in Fig. 1, i. e., viewing it toward the discharge faces of the scarfing tips; and

15 Figs. 4, 5 and 6 are diagrammatic views showing the positions assumed by the scarfing tips and their associated parts when scarfing work-pieces of different cross-sectional dimensions.

The scarfing apparatus in its preferred form comprises a base 10 (Figs. 1 and 2) and a superstructure mounted thereon having a portion 11 which overhangs the base and extends transversely over the conveyor rolls 12 of a mill table on which a work-piece W to be scarfed (Figs. 2 and 3) such as a billet, slab, or the like, is supported and fed through the scarfing apparatus in the usual way. An arm 13 depends from the portion 11 of the superstructure (Figs. 1 and 2) and pivotally supports a pair of tip arm carriers shown at 14 and 15, one at each side of the apparatus.

20 Each of the tip arm carriers is pivotally mounted at its rear end on the arm 13 to swing about a vertical axis. This is preferably accomplished by providing a pair of bosses 16 and 17 on each tip arm carrier which are pivotally connected to similar bosses 18 and 19 by a pivot or hinge pin 20. A pair of tip arms are pivotally mounted in each of the carriers 14 and 15. The two tip arms that are mounted in the carrier 14 are shown at 21 and 22 in Fig. 1 and the two that are mounted in

25 the carrier 15 are shown at 23 and 24 in this figure. Each of the tip arms is mounted in its carrier to pivot about a horizontal axis 25 (Fig. 2). Thus the forward end of each of the tip arms is movable vertically. The tip arm 21 is operatively connected to the piston of a fluid cylinder 26 adapted when supplied with motive fluid such as air to lift the forward end of the arm and swing it about its horizontal pivot axis 25. Weights 27 supported by the rear end of the

30 tip arm 21 counterbalance a portion of the weight of the forward end of the arm and reduce the load imposed on the hydraulic motor 26. When the motive fluid is discharged from the cylinder 26 the forward end of the tip arm 21 moves downward due to its own weight. Each of the other tip arms is similarly counterweighted at its rear end, the weights for the arm 22 being shown at 28 in Fig. 1, and each of the other arms has a similar fluid cylinder adapted to effect pivotal 35 movement about its horizontal pivot axis 25. The

40 45 50 55 60

fluid cylinders for the tip arms 22, 23 and 24 are shown at 29, 30 and 31, respectively, in Fig. 1. However, the fluid cylinder 29 associated with the tip arm 22 may remain idle or entirely disconnected, if desired, since the forward end of this tip arm can, and preferably is, raised when necessary by connections with the tip arms 21 and 23 when the forward ends of these arms are raised as will hereinafter more fully appear.

The forward end of the tip arm 21 carries a rigid tubular member 32 which extends transversely of the apparatus and transversely over the work-piece W. This member is secured to the tip arm 21 by means of a clamp 33 (Fig. 3) attached to the tip arm by bolts 34. Keys 35 prevent the clamp from turning on the tip arm. The upper horizontal torch tip T₁, i. e. the one that is intended to scarf the top face of the work-piece, is connected to the tubular member 32 by means of brackets 36 attached to a plate 37 which in turn is secured to the torch tip by bolts 38. In Fig. 3 the other torch tips are shown at T₂, T₃ and T₄, the tips T₂ and T₄ being the vertically disposed tips for scarfing the vertical side faces of the work-piece and the tip T₃ being the other horizontal tip for scarfing the bottom face of the work-piece.

The forward end of the tip arm 23 carries a member 39 which extends transversely of the apparatus and transversely under the work-piece W as shown in Fig. 3. This member is secured to the tip arm 23 by a clamp 40 attached to the tip arm by bolts 41. The keys 42 prevent the clamp from turning on the tip arm. The transversely extending member 39 supports the horizontal tip T₃ for scarfing the bottom face of the work-piece.

The torch tip T₂ is attached to the forward end of the tip arm 22 by a clamp 43 secured to the tip arm by bolts 44 and prevented from turning on the arm by means of keys 45. A retaining plate 46 connects the torch tip to the clamp 43.

In a similar manner, the torch tip T₄ is secured to the forward end of the tip arm 24 by means of a clamp 47 attached to the tip arm by bolts 48 and prevented from turning on the tip arm by keys 49.

Referring to Figs. 1 and 2, lever arms 50 and 51 are secured, respectively, to the rear ends of tip arm carriers 14 and 15. The rear ends of the lever arms 50 and 51 are operatively connected to the pistons of fluid cylinders 52 and 53, respectively, (Fig. 1). These fluid cylinders are double-acting. When motive fluid such as air is admitted to the rod end of the cylinder 52, the carrier 14 in which the tip arms 21 and 22 are mounted is moved about the axis of its pivot pin 20 in a direction such that the forward end of the carrier moves outward away from the work-piece, and when motive fluid is admitted to the head end of the cylinder the carrier is moved in the opposite direction to move its forward end inward toward the work-piece. The other carrier 15 in which the other two tip arms 23 and 24 are mounted is moved in a similar manner by admitting air or similar motive fluid to the rod end or the head end of the fluid cylinder 53. The tip arms 21 and 22 being mounted in the carrier 14 partake of its movement about its pivot pin 20, and similarly, the tip arms 23 and 24 being mounted in the carrier 15 move with it when it is swung about its pivot pin. Therefore, it will be seen from Fig. 3 that when the forward end of the carrier 14 moves horizontally in either direction the forward ends of the two tip arms 21

and 22 will move horizontally in unison and the two torch tips T₁ and T₂ carried by them will also move horizontally in unison. In other words, the horizontal distance or relationship between the torch tips T₁ and T₂ never changes. However, since the forward ends of the tip arms 21 and 22 can be moved vertically independently of each other, the torch tips T₁ and T₂ can also be moved vertically independently of each other. Similarly, when the forward end of the carrier 15 is moved horizontally, the forward ends of the tip arms 23 and 24 will be moved horizontally in unison and the tips T₃ and T₄ carried by them will also move horizontally in unison. Thus the horizontal relationship between the tips T₃ and T₄ never changes although each tip can be moved vertically independently of the other because the forward ends of the tip arms 23 and 24 are independently movable in a vertical direction.

A stop arm 54 extending upward from the tip arm 24 abuts at its upper end against a plate 55 on the under surface of the tubular transverse member 32. The stop arm is of such length that the forward end of the tip arm 24 can never approach the transverse member 32 close enough to cause the upper end of the tip T₄ to strike the left end of the tip T₁ in Fig. 3 when there is relative horizontal movement between the two tips. When the forward ends of the tip arms 21 and 22 are moved horizontally relative to the forward ends of the tip arms 23 and 24, thereby causing relative horizontal movement between the transverse member 32 and the stop arm 54, the upper end of the stop arm slides on the plate 55, or vice versa. A similar stop arm 56 extends downward from the forward end of the tip arm 22 and abuts at its lower end against the upper surface of the lower transverse member 39. Thus the forward end of the tip arm 22 can never approach the transverse member 39 close enough to cause interference between the lower end of the tip T₂ and the right end of the tip T₃ in Fig. 3 when these two tips are moved relatively in a horizontal direction. When there is relative horizontal movement between the forward end of the tip arm 22 and the transverse member 39, the lower end of the stop arm 56 slides on the upper surface of the member 39, or vice versa.

A stop device 57 is secured to the clamp 47 and cooperates with the stop arm 54 to limit the approach of the two transverse members 32 and 39.

A member 58 (Fig. 3) is attached to the clamp 33 by the clamping bolts 34 and projects inwardly far enough to engage the clamp 43 when the forward end of the tip arm 21 is moved upward by its fluid cylinder from the position shown in Fig. 3 to a position in which the lower right corner of the tip T₁ is about even with the upper left corner of the tip T₂. This position of the parts is shown in Fig. 4. Further upward movement of the tip arm 21 to the neutral position hereinafter described will move the tip arm 22 along with it to the latter's neutral position. Thus, movement of the tip arm 21 to its neutral position moves both the torch tip T₁ and the torch tip T₂ to the upper limit of their vertical movement. Similarly, a member 59 (Fig. 3) attached to the clamp 40 by the clamping bolts 41 projects inward far enough to engage the clamp 47 when the tip arm 23 moves downward from the position shown in Fig. 3 far enough to bring the upper left corner of the tip T₃ about even with the lower right corner of the tip T₄ as shown in Fig. 4. Further downward movement of the tip arm 23 then moves the tip arm 24 downward.

ly along with it, thus moving both the torch tips T_3 and T_4 to the lower limit of their vertical movement.

The torch tips may be of any suitable type, the particular ones shown in the drawings being of the block type having a row of drilled jet passages from whose discharge orifices the scarfing oxygen jets issue. In Fig. 3 the tips are viewed in a direction looking toward their discharge faces. The discharge face of each tip is shown at 61 in Figs. 1, 2 and 3 and the discharge orifices from which the scarfing oxygen jets issue are shown at 62. The scarfing jets are projected at an angle against the corresponding surface of the work-piece to scarf or desurface it thermo-chemically when the surface metal is at kindling temperature, as is well understood in the art. Each torch tip may also be adapted to project preheating flames from the discharge face of the tip onto the surface of the work-piece to heat the surface metal to kindling temperature. While the portions of the torches from which the scarfing jets and the preheating flames issue have been referred to as "scarfing tips" it should be understood that this term is used to apply also to so-called "scarfing heads" having a row of individual nozzles through which the scarfing jets issue instead of passages drilled directly in metal blocks.

The various pipes, conduits, and hoses usually employed for conducting the scarfing oxygen, the preheating gases, and the cooling fluid, to the torch tips have not been shown in the drawings for the sake of clarity.

The scarfing operation may be controlled remotely in accordance with conventional practice by solenoid valves, electric switches etc.—none of which have been shown in the drawings because they form no part of the invention. Moreover, the piping system for conducting motive fluid to and from the fluid cylinders, and the control system for the fluid cylinders, have not been illustrated. Any suitable control system for them may be used whereby the fluid cylinders may be separately or simultaneously controlled, or controlled in any desired combination.

The neutral position of the parts is not shown in the drawings but it is the position assumed by the parts when the forward ends of the tip arms 21 and 22 are in their highest and outermost position and the forward ends of the tip arms 23 and 24 are in their lowest and outermost position. In other words, the forward ends of the tip arms 21 and 22 and the pair of torch tips T_1 and T_2 would be in a higher and more outward position than shown in Fig. 4 and the forward ends of the tip arms 23 and 24 and the pair of torch tips T_3 and T_4 would be in a lower and more outward position than shown in this figure. Ample passage is then provided for introduction of the end of the work-piece into the expanded opening between the torch tips. The torch tips are moved to neutral position after each scarfing operation. Now assuming that the work-piece W in Fig. 4 is a work-piece of the maximum size that the apparatus is adapted to scarf, and that it has been fed into the scarfing apparatus far enough for its forward end to be in operative relation with the torch tips when they are moved inwardly against it, motive fluid is admitted to the head end of the cylinders 52 and 53 to swing the tip arm carriers inwardly, and motive fluid is also admitted to the cylinders 30 and 31 to raise the forward ends of tip arms 23 and 24, and the motive fluid is released from the cylinder

26 to allow the forward ends of tip arms 21 and 22 to descend by their own weight. The fluid cylinders may be operated in this manner either simultaneously or successively. In any event the 5 result is that the two pairs of scarfing tips, i. e., the pair T_1 and T_2 and the pair T_3 and T_4 , are moved horizontally inward until the tip T_2 engages the right vertical face of the work-piece as viewed in Fig. 4 and the tip T_4 engages the 10 left vertical face of the work-piece. The downward movement of the forward end of tip arm 21 lowers the upper horizontal tip T_1 until it rests on the top face of the work-piece, and the raising of the forward end of the tip arm 23 brings the 15 lower horizontal tip T_3 against the bottom face of the work-piece. The tip T_4 will be raised by its tip arm 24 until the stop 54 abuts against the transverse member 32 on the tip arm 21. This 20 stop prevents the tip T_4 from ever being raised beyond the level at which the upper end of this tip is substantially flush with the discharge face of the tip T_1 and hence substantially flush with the top face of the work-piece. The forward end of the tip arm 22 which was held in its raised 25 neutral position by the member 58 on the tip arm 21, descends by its own weight, when the forward end of the tip arm 21 is lowered, until the stop 56 abuts against the lower transverse member 33 connected to the tip arm 23. The 30 stop 56 prevents the tip T_2 from ever being lowered beyond the level at which its lower end is substantially flush with the discharge face of the lower horizontal tip T_3 and hence substantially flush with the bottom face of the work-piece. 35 The torch tips will now be in the position shown in Fig. 4 with the full effective length of each tip being utilized to scarf the corresponding face of the work-piece. In other words, the tips do not overlap but the entire width of each 40 tip is active and extends from one edge of the corresponding surface of the work-piece to the other. Larger work-pieces than that represented in Fig. 4 can be scarfed by increasing the effective widths of the tips and making appropriate 45 changes in the length of the stop arms 54 and 56.

If the work-piece to be scarfed has the same width as the work-piece shown in Fig. 4 but has a smaller vertical dimension, the torch tips will 50 be moved to the position shown in Fig. 5. The inward horizontal movement of the two pairs of tips will take place as described in connection with Fig. 4, but the tip arm 21 and the upper horizontal tip T_1 carried by it will descend farther as shown in Fig. 5 to bring the tip T_1 into engagement with the newly located top face of the work-piece. As above stated, the stop arm 54 will always keep the upper end of the tip T_4 substantially flush with the discharge face of the tip T_1 55 when the tips are in operative position, and therefore the tip T_4 will now be positioned as shown in Fig. 5 with its upper end substantially flush with the newly located top face of the work-piece on which the tip T_1 rests. The lower end of the 60 tip T_4 will therefore vertically overlap the lower horizontal tip T_3 and the upper end of the tip T_2 will vertically overlap the upper horizontal tip T_1 as shown in Fig. 5, this being permitted because the tips T_1 and T_2 have independent relative vertical movement and the tips T_3 and T_4 likewise have independent relative vertical movement.

The particular machine illustrated in the drawings is not adapted to scarf work-pieces whose vertical dimension is any less in its relation to 65 the width of the tips than the vertical dimension

70
75

of the work-piece represented in Fig. 5, because the stop 51 prevents further vertical approach of the two horizontal tips T₁ and T₃. The stop 51 could be designed to allow closer approach of the horizontal tips T₁ and T₃ and thus permit scarfing of still thinner work-pieces, but the principal function of the stop 51 is to prevent the tips from coming together after the work-piece has passed beyond them, and it must therefore hold the tips T₁ and T₃ at some minimum vertical spacing when there is no work-piece between them, and in Fig. 5 the vertical dimension of the work-piece is assumed to correspond to this desired minimum spacing between the horizontal torch tips. The distance that the vertical tips T₂ and T₄ can approach each other in a horizontal direction is determined by the length of the stroke of the pistons of fluid cylinders 52 and 53, these tips being shown at the inner limit of their horizontal movement in Fig. 6.

In Fig. 6 the work-piece W is represented as having a smaller horizontal dimension than the work-piece in Fig. 5 but the same vertical dimension. By comparing Figs. 5 and 6 it will be seen that the tips are positioned against the four faces of the work-piece in the same manner as described in connection with Fig. 5 except that the tip arms 21 and 22 have been given at additional inward horizontal movement to bring the vertical tips T₂ and T₄ closer together horizontally. Since the tips T₁ and T₂ move horizontally in unison (as do the tips T₃ and T₄), the upper horizontal tip T₁ will now horizontally overlap the upper end of the tip T₄ and the lower horizontal tip T₃ will horizontally overlap the lower end of the tip T₂ as shown in Fig. 6.

The billet or other work-piece to be scarfed is usually fed to and through the scarfing apparatus by power-driven conveyor rolls on which the work-piece is supported, and therefore the bottom face of the work-piece, regardless of the cross-sectional dimensions of the work-piece, will always be at substantially the same elevation. Moreover, a stationary guide is usually placed along the roller bed in advance of the scarfing apparatus against which one side of the billet, or other work-piece, slides as it is delivered to the scarfing apparatus. Usually the guide is positioned so that the left vertical face of the work-piece engages it. In this case the left vertical face of the work-piece will always occupy the same vertical plane regardless of the cross-sectional dimensions of the work-piece. When such a guide is used and when the work-piece is fed to and through the scarfing apparatus by conveyor rolls on which the work-piece is supported, the forward end of the tip arm 23, and the lower horizontal tip T₃ carried by it, will always be moved from neutral position to the same operative position. Moreover, the forward end of the tip arm 24, and the tip T₄ carried by it, will never be farther to the right than shown in Figs. 4, 5 and 6 when the tip T₄ is against the left vertical face of the work-piece.

As above stated, the tips are returned to neutral or inoperative position after each scarfing operation, i. e., the forward ends of the tip arms 21 and 22, and the tips T₁ and T₂ carried by them, are moved upward and outward, and the forward ends of tip arms 23 and 24, and the tips T₃ and T₄ carried by them, are moved downward and outward from the position shown in Fig. 4. The forward end of arm 21 in moving upward will bring the member 58 into contact with the clamp

43, and therefore the arm 22 will be moved upward by the arm 21. Since the forward ends of both arms are moved downward by their own weight, the one fluid cylinder that raises the forward end of tip arm 21 suffices to operate both tip arms 21 and 22. Similarly, when fluid is released from the cylinders 30 and 31 to permit the forward ends of tip arms 23 and 24 to descend to neutral position by gravity, the member 59 on the tip arm 23 engages the clamp 47 and insures that the forward end of tip arm 24 moves downward to neutral position along with the forward end of tip arm 23.

When the scarfing tips are in overlapping relation as in Figs. 5 and 6, so that two or all of the tips project beyond the corresponding faces of the work-piece, the effective length of each projecting tip is preferably altered so that it will conform to the width of the surface which it scarfs. This may be accomplished by plugging the outlet orifices from which the preheating flames and the scarfing oxygen jets issue in the portion of each tip that projects beyond the corresponding surface of the work-piece, or by shutting off the supply of preheating gases and scarfing oxygen to such orifices by suitable valves.

It will now be seen that the apparatus is adapted to simultaneously scarf all four faces of a billet or other work-piece regardless of the cross-sectional dimensions of the work-piece provided they fall within predetermined maximum and minimum limits. For any size work-piece within those limits each tip will move toward scarfing position until it engages the corresponding surface of the work-piece, and despite the overlapping relation that the tips must assume for work-pieces which are smaller than the maximum size work-piece that the apparatus is adapted to scarf, and despite the substantially coplanar relation they sometimes assume, there is no interference between the tips, nor can the apparatus be so operated as to cause them to interfere. Each tip always moves to and from operative position at all times without contacting with any other tip. This is due principally to the mounting of the tips which permits horizontal and vertical movements of each tip, the preserved horizontal distance or relationship between the two tips of each pair, the fact that each tip of each pair can move vertically independently of the other tip, and to the stop arrangement described.

I claim:

1. Apparatus for scarfing billets, blooms, slabs, and the like, comprising a tip arm carrier at each side of the apparatus, a pair of tip arms mounted in each carrier and extending longitudinally of the billet or the like to be scarfed, the two tip arms in each carrier being pivotally mounted therein for independent movement in vertical planes about horizontal axes, each of said carriers being pivotally mounted for movement about a vertical axis whereby the forward ends of the two tip arms carried by it are movable in unison horizontally, a horizontally disposed scarfing tip mounted on the forward end of one tip arm of each pair and a vertically disposed scarfing tip mounted on the forward end of the other tip arm of each pair, the scarfing tips thus mounted on the tip arms constituting two pairs of right-angled related tips one of which pairs of tips is adapted to scarf the top face and one vertical face of the work-piece and the other of which pairs of tips is adapted to scarf the bottom face and the other vertical face of the work-piece,

actuating means for moving said tip arms about their horizontal axes to adjust the scarfing tips vertically, and actuating means connected to said carriers for moving them about their vertical axes to adjust the two pairs of scarfing tips horizontally.

2. Apparatus in accordance with claim 1 having stop means operatively positioned between the tip arm that carries the horizontal tip of one pair of tips and the tip arm that carries the vertical tip of the other pair of tips to prevent relative vertical movement between the forward ends of such tip arms which would cause the vertical tip to vertically overlap the horizontal tip.

3. Apparatus for scarfing billets, blooms, slabs, and the like, comprising a tip arm carrier at each side of the apparatus, a pair of tip arms mounted in each of said carriers and extending longitudinally of the billet or the like to be scarfed, one tip arm of each pair being an inner tip arm and the other being an outer tip arm, the two tip arms of each pair being pivotally mounted in the corresponding carrier for independent movement in a vertical plane about a horizontal axis whereby the forward end of each tip arm of the pair is movable vertically, each of said carriers being movable about a vertical axis whereby the forward ends of the tip arms mounted in it are movable horizontally in unison, a transverse member connected to the forward end of the outer tip arm of each pair, one of said members extending transversely over the work-piece and the other extending transversely under the work-piece, a horizontally disposed scarfing tip carried by each of said transverse members, a vertically disposed scarfing tip carried by the forward end of the inner tip arm of each pair, the scarfing tips thus supported on the tip arms constituting two pairs of right-angularly related tips one of which pairs of tips is adapted to scarf the top face and one vertical face of the work-piece and the other of which pairs of tips is adapted to scarf the bottom face and the other vertical face of the work-piece, and means for actuating the tip arms about said axes to adjust the scarfing tips horizontally and vertically.

4. Apparatus in accordance with claim 3 having stop means positioned between the inner tip arm of each pair and the transverse member connected to the outer tip arm of the other pair and operating to prevent the vertically disposed tip of each pair of tips from vertically overlapping the horizontal tip of the other pair.

5. Apparatus for scarfing billets, blooms, slabs, and the like, comprising a pair of tip arms at each side of the apparatus extending longitudinally of the billet or the like to be scarfed, the two tip arms of each pair being mounted for pivotal movement about vertical and horizontal axes whereby the forward ends of the arms are movable horizontally and are independently movable vertically, a horizontally disposed scarfing tip mounted on the forward end of one tip arm of one pair for scarfing the top face of the work-piece, a vertically disposed scarfing tip mounted on the forward end of the companion tip arm of the same pair for scarfing the adjacent vertical face of the work-piece, a second horizontally disposed scarfing tip mounted on the forward end of one tip arm of the second pair for scarfing the bottom face of the work-piece, a second vertically disposed scarfing tip mounted on the forward end of the companion tip arm of the second pair for scarfing the other vertical face

of the work-piece, means for actuating the tip arms about said axes to adjust the scarfing tips horizontally and vertically, and a member on the forward end of the tip arm that carries the upper horizontal scarfing tip adapted after predetermined upward movement of such arm to engage the companion arm of the same pair whereby when the upper horizontal tip is raised to the upper limit of its travel by its tip arm the vertical tip carried by the companion tip arm is also raised to the upper limit of its travel.

6. Apparatus in accordance with claim 5 having a member on the forward end of the tip arm that carries the lower horizontal scarfing tip adapted after predetermined downward movement of such arm to engage the companion arm of the same pair whereby when the lower horizontal tip is lowered to the lower limit of its travel by its tip arm the vertical tip carried by the companion tip arm is also lowered to the lower limit of its travel.

7. Apparatus for simultaneously scarfing the four surfaces of rectangular ferrous metal bodies comprising four scarfing tips each of which is adapted to be positioned adjacent one of the work surfaces to be scarfed and being substantially as wide as the widest such surface the apparatus is designed to scarf, supporting means for supporting the tips with their inner faces in rectangular formation so that they define a central opening for the body to be scarfed and including two pairs of members, each member of each pair rigidly supporting one tip of a pair of contiguous angularly related tips, a common carrier for the two members of each pair, each carrier being movable to effect unitary movement in one direction of the two members carried by it, and the two members of each pair being pivotally mounted in their carrier for relative movement in a second direction at right angles to the first direction whereby when the members of each pair are actuated to move the two contiguous tips carried by them to operative position with respect to the corresponding work surfaces the inner face of one tip of the pair can overlap the end of the second tip in the direction in which the members are relatively movable but the inner face of the second tip cannot overlap the end of the first tip in the direction in which the members are unitarily movable, actuating means operatively connected to said members, and stop means for preventing each tip whose one end is capable of being overlapped by the inner face of a contiguous tip from having its other end overlapped by the inner face of the tip contiguous to that end.

8. Apparatus in accordance with claim 7 in which said stop means is positioned between the two members which support the two tips whose overlapping is prevented by the stop means.

REIDAR J. NICOLAISEN.
